UNITED STATES PATENT OFFICE.

ARMIN C. H. AREND, OF CINCINNATI, OHIO.

DESIGN FOR A BADGE, PIN, EMBLEM, CHARM, OR SIMILAR ARTICLE.

58,695.

Specification for Design.

Patented Aug. 30, 1921.

Application filed March 24, 1921. Serial No. 455,167. Term of patent 14 years.

To all whom it may concern:

Be it known that I, ARMIN C. H. AREND, a citizen of the United States of America, and resident of Cincinnati, in the county of Hamilton and State of Ohio, have invented a new, original, and ornamental Design for a Badge, Pin, Emblem, Charm, or Similar Article, of which the following is a specification, reference being had to the accompanying drawing, forming part thereof.

The figure is a front elevation of a badge or similar article showing my new design.

I claim:

The ornamental design for a badge, pin, emblem, charm or similar article, as shown.

ARMIN C. H. AREND.
